COMBINED REAR PROJECTION VIEWER AND CLOCK

Willis L. Wells, Clayton, Mo., assignor to VueTech
Corporation, St. Louis, Mo.

Filed May 13, 1970, Ser. No. 22,945

Term of patent 14 years

Int. Cl. D16—02

U.S. Cl. D61—1

FIG.1

FIG.2

FIG.3

FIG.4

FIG. 1 is a top plan view of a combined rear projection viewer and clock showing my new design.

FIG. 2 is a front elevational view thereof.

FIG. 3 is a right side elevational view thereof, and
FIG. 4 is a left side elevational view thereof.

The rear and the bottom of the machine, not shown, are substantially plain and unornamented.

I claim:

The ornamental design for a combined rear projection viewer and clock, substantially as shown and described.
